UNITED STATES PATENT OFFICE.

WARREN T. REASER, OF FAIRMONT, NEBRASKA, ASSIGNOR TO THE ROUND VALVE COMPANY, OF CHICAGO, ILLINOIS.

BALANCED OSCILLATING VALVE.

SPECIFICATION forming part of Letters Patent No. 363,765, dated May 24, 1887.

Application filed December 18, 1886. Serial No. 221,953. (No model.)

To all whom it may concern:

Be it known that I, WARREN T. REASER, a citizen of the United States, residing at Fairmont, in the county of Fillmore and State of Nebraska, have invented certain new and useful Improvements in Balanced Oscillating Valves for Steam-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improvement in balance-valves for locomotives or other steam-engines, the object being to construct a balance-valve that may be applied to locomotive or other similar slide-valve engines by removing the ordinary slide-valve and substituting my improved valve by bolting it to the valve-face, leaving the old cylinder and steam-chest intact, and necessitating no change, except to drill the side of the steam-chest and bolt on a stuffing-box to allow the passage of the valve-stem through the side of the steam-chest.

In the drawings, Figure 1 is a vertical longitudinal section of a steam-cylinder furnished with my improved valve. Fig. 2 is a cross-section of the same through the dotted line $x-x$ in Fig. 1, and Fig. 3 is an enlarged detail showing a section through the packing.

The valve is so constructed that the steam is admitted at the ends, pressing equally on all sides, and would without other change be perfectly balanced, except the area of the steam-ports $h-h$. The holes $e-e$ in the top of the valve are, however, made of sufficient area to compensate for the port-openings and back-pressure of the exhaust.

A is an ordinary steam-engine cylinder.
B is the steam-chest.
C is my improved valve, bolted to the seat.
D is the induction-pipe.
E is the exhaust-pipe.
a is the casing of my improved valve, made in halves for convenience of taking up the wear and to facilitate adjustment, the upper and lower parts of said casing being connected by bolts $i-i$, as shown in Fig. 1.

b is a crank-arm attached to the valve stem d , and shows how the eccentric-rod may be attached to the valve.

k is the stuffing-box, which, when the improved valve is attached to an old engine, is bolted or otherwise secured to one side of the steam-chest, but in new engines may be cast integral with said steam-chest.

$c-c$ are packing-rings let into a groove in the ends of the casing a , for the purpose of keeping the ends of the valve tight, flanges being formed on each end of said valve for the ring to bear against. Small holes $a'-a'$ in the casing admit steam behind the rings, keeping them up against the flanges of the valves C .

$e-e$ are openings of suitable area through the top of the valve to counterbalance the steam-ports $h-h$ and back-pressure of the exhaust. By this construction I produce cheaply a perfectly-balanced oscillating valve that may be readily applied to any ordinary slide-valve engine, relieving it from the great pressure of the steam upon such slide-valves, the use of which valves increases the friction to be overcome by the steam-pressure, and consequently reduces the effective power of the engine. This reduction in effective power is obviated by my improved valve, which, being perfectly cylindrical and without taper, is not liable to stick or have its friction greatly increased by expansion, as is frequently the case with oscillating valves having a taper; and, further, the ends of my valve being provided with a spring-packing the pressure of which upon the flanges is regulated by the pressure of the steam used, no more friction is generated at these joints than is absolutely required to keep a tight joint between the valve and its casing.

I am aware that it is not new to balance the slide-valves of steam-engines; neither is it new to partially balance the pressure of the steam upon oscillating valves. I do not, therefore, broadly claim such a device, but limit the same to the especial construction shown and described in this specification.

Having thus described my invention, I claim as new, and desire to secure by Letters Patent, the following:

1. In balanced oscillating valves for steam-engines, the combination, with a valve-casing,

a, adapted to be bolted to the face of an engine-cylinder within the steam-chest, and provided with facing-rings *c c*, and openings *a' a'*, to admit steam behind the packing, of an oscillating cylindrical valve, *C*, provided with flanged ends fitting over the packing-rings and having openings *ee* of an area equal to the area of its valve-ports *hh*, to balance the loss of pressure upon one side of the valve caused by said ports, substantially as described.

2. In a steam-engine, the combination, with the engine-cylinder *A* and a steam-chest, *B*, bolted to said cylinder, of the valve-casing *a*,

bolted to the valve-face of the cylinder, and provided with packing-rings *ee* and openings *a' a'*, and the oscillating cylindrical valve *C*, inclosed in said casing and provided with flanged ends fitting over said packing-rings, said valve having ports *hh* and counterbalance-openings *ee*, substantially as described.

In testimony whereof I affix my signature in presence of two witnesses.

WARREN T. REASER.
